UNITED STATES PATENT OFFICE

135,029

DESIGN FOR A SHARPENER FOR RAZOR BLADES

Walter Griffies, Chicago, Ill.

Application June 17, 1942, Serial No. 107,222

Term of patent 7 years

To all whom it may concern:

Be it known that I, Walter Griffies, a citizen of the United States, residing at Chicago, in the county of Cook and State of Illinois, have invented a new, original, and ornamental Design for a Sharpener for Razor Blades, of which the following is a specification, reference being had to the accompanying drawing, forming part thereof.

I claim:

The ornamental design for a sharpener for razor blades, as shown.

WALTER GRIFFIES.
